UNITED STATES PATENT OFFICE.

ANNA B. MAHONEY, OF VACAVILLE, CALIFORNIA.

SHOULDER-STRAP HOLDER FOR ARMPIT SHIELDS.

Application filed October 1, 1925. Serial No. 59,877.

This invention relates to a shoulder strap holder for arm pit shield.

The primary object of the invention is to provide a shoulder strap holder and attached arm pit shield, the holder being adapted to retain the straps of lingerie, brassières, etc., on the shoulders of the wearer while the arm pit shield is attached to the holder to prevent the former from being 10 worked out of position.

Other objects and advantages of the invention will be apparent during the course of the following description.

In the accompanying drawing forming a 15 part of this specification and in which like numerals are employed to designate like parts throughout the same,

Figure 1 is a schematic view of the article embodying this invention and illustrates the 20 manner in which it is used, and

Figure 2 is a perspective view of the shoulder strap holder and arm pit shield embodying this invention.

In the drawing, wherein for the purpose 25 of illustration is shown a preferred embodiment of this invention, the numeral 5 designates in its entirety the shoulder strap holder which is attached to the garment strap 6 in the manner illustrated and has connected 30 thereto the strap 7 which supports and holds the arm pit shield designated in its entirety by the reference character 8.

In Fig. 2 the shoulder strap holder 5 is clearly illustrated as including an elongated 35 body portion 9 having the laterally projecting, centrally located ears 10. The end portions of the elongated body 9 are provided with the struck-up lugs 11 while the ears 10 and the adjacent portion of the body part 40 9 are formed with the struck-up lugs 12. These lugs are intended to permit the shoulder strap 6 to be positioned therebeneath and clamped thereby against the body portion 9. It is intended that this entire holder 5 be 45 formed of a flexible material or composition, such as celluloid or other similar material. The forming of the holder 5 out of celluloid, or the like, will permit the lugs 11 and 12 to be of a semi-rigid nature so that they will 50 securely clamp the shoulder strap 6 to the body portion 9.

The arm pit shield 8 is intended to be made of rubber, or other suitable material,

of a sufficient firmness to prevent it from becoming wrinkled or crumpled and the upper 55 part to have an automatic action when raising and lowering the arm. The shield includes a front portion 13, an upper part 14 intended to engage the arm pit, and the lower portion 15 which is intended to bear 60 against the body of the user. Attached to this shield 8 are the ends of a strap or band 7 which is intended to be attached to the holder 5 in the manner best illustrated in Fig. 2, i. e., with the intermediate portion 65 of the strap or band 7 underlying the lugs 11 and 12 and when the garment strap 6 is attached to this holder 5, the shield strap 7 will also underlie the garment strap 6.

It will now be apparent that the holder 5 will prevent the garment strap 6 from slipping down off of the shoulder of the user onto the arm and will thereby overcome any 70 danger of the garment strap 6 becoming severed due to the strain placed thereupon 75 when the wearer exercises her arm. The attaching of the shield strap or band 7 to the holder 5 will insure the retaining of the shield 8 in the proper position and, thereby, eliminate all danger of the shield working 80 around the arm and shoulder of the wearer.

It is to be understood that the form of this invention herewith shown and described is to be taken as a preferred example of the same, and that various changes in the shape, 85 size, and arrangement of parts may be resorted to without departing from the spirit 90 of the invention or the scope of the subjoined claims.

Having thus described the invention, I 95 claim:

1. A device of the character described comprising an elongated plate having a pair of similar transverse loop elements struck upwardly from the ends thereof in aligned 95 relation longitudinally of the plate for reception of a shoulder strap of an arm pit shield, said plate further having a larger transverse loop element struck upwardly from the intermediate portion thereof for 100 reception of the wider shoulder strap of a body garment.

2. A device of the character described comprising an elongated plate having a pair of similar transverse loop elements struck 105 upwardly from the ends thereof in aligned

relation longitudinally of the plate for reception of a shoulder strap of an arm pit shield, said plate further having a larger transverse loop element struck upwardly from the intermediate portion thereof for reception of the wider shoulder strap of a body garment, each of said loops being trans-

versely split to facilitate engagement of the shoulder straps therein and embodying a pair of similar lugs projecting toward each other, transversely of the plate. 10

In testimony whereof I affix my signature.

ANNA B. MAHONEY.
